UNITED STATES PATENT OFFICE.

EUGENE F. DAVENPORT, OF MELROSE, MASSACHUSETTS, ASSIGNOR TO UNITED SHOE MACHINERY COMPANY, OF PATERSON, NEW JERSEY, A CORPORATION OF NEW JERSEY.

TRANSMITTING DEVICE.

1,078,664.

Specification of Letters Patent. Patented Nov. 18, 1913.

Application filed May 11, 1909. Serial No. 495,335.

To all whom it may concern:

Be it known that I, EUGENE F. DAVENPORT, a citizen of the United States, residing at Melrose, in the county of Middlesex and State of Massachusetts, have invented certain Improvements in Transmitting Devices, of which the following description, in connection with the accompanying drawings, is a specification, like reference characters on the drawings indicating like parts in the several figures.

This invention relates to machines for treating stock and more particularly to that class of such machines in which the stock is operated upon by a plurality of separate and successively acting instrumentalities while passing through the machine. For example one of the instrumentalities referred to may comprise means for engaging and feeding the stock which is to be operated upon by other instrumentalities.

One object of this invention relates to novel means for controlling the operation of instrumentalities such as those referred to above so that said instrumentalities shall always be set in motion in a certain order, whereby one cannot be set in motion until certain predetermined others have first been started; and preferably the various instrumentalities will be stopped successively in the reverse order of their starting. In the chosen embodiment of this invention, wherein a skiving machine is shown, the control of the stock treating instrumentalities (shown as a feeding mechanism and a knife) is effected by a controlling device which, when actuated by the operator, applies power first to the knife and then to the feeding mechanism; but it should be understood that this particular embodiment of the invention is used for the purpose of illustration only. This feature of the invention, however, is very desirable in a skiving machine since it is necessary that the knife shall be revolving when the stock is presented to it.

Another object of this invention relates to means for varying the effect of one of the operating instrumentalities without varying the effect of other of said instrumentalities. Here again is a feature of wide application which can be conveniently illustrated as applied to a skiving machine, since in machines of this class it is desirable when operating upon spongy stock or upon stock

having an irregular outline that the stock shall be fed more slowly while at the same time the knife shall continue its motion at full speed.

These and other features of the invention including certain details of construction and combinations of parts will be explained in connection with the following description of a machine and will be pointed out more definitely in the claims.

Referring now to the accompanying drawings:—Figure 1 is a side elevation of a skiving machine, Fig. 2 is an end elevation of the upper portion thereof, and Fig. 3 is a vertical sectional view taken on the line 3—3 of Fig. 2, with the abutment and its allied parts shown in full lines and with certain parts including the housing and the driving shaft broken away. This figure shows the clutch which connects the driving pulley with the shaft thrown in.

1 indicates the base which supports the frame 3, in bearings 5 of which the driving shaft 7 is journaled. The shaft 7 is driven from the pulley 9 through connections to be hereinafter more fully described and is provided with worm gears 11 and 13 which intermesh with gears 15 and 17 carried by shafts 19 and 21 respectively. The shaft 19 is actuated through a friction clutch 23 indicated by dotted lines in Fig. 1, and on its lower end is mounted a work feeding disk 25 while the shaft 21 through the medium of the bevel gears 27 and 29 drives the horizontal shaft 31 on the end of which a feed roll 33 is mounted. An edge guide is indicated at 35. The disk knife 37 to which the stock is fed by disk 25 and roll 33 is carried on the lower end of a shaft 39 which is mounted in bearings 41 and is actuated by a belt 43 driven from a pulley 45. A grinding device (not shown) is driven from a pulley 47 by means of a belt 49.

The machine as thus far described is substantially the same as that disclosed in Letters Patent No. 823,586 granted to me on June 19, 1906.

Various parts of the machine shown in the accompanying drawings such as the means for adjusting the knife and the means for adjusting the grinder will not be described here because the present invention is not concerned with them. It is clear, however, from the parts thus far described that the machine is provided with a plural-

ity of instrumentalities for acting upon stock; first the disk 25 and roll 33 with their allied parts acting in this case to feed the stock and second the disk knife 37 with its allied parts which act in this case to skive the stock. And it should be understood that the machine has been chosen as a typical one because of the presence of these instrumentalities, since the mechanism which is about 5 to be described relates to the control of instrumentalities of which these may be said to be a type. In order to control these stock treating instrumentalities in the manner desired a belt shifting device and a friction 10 clutch are provided.

Referring more particularly to Figs. 2 and 3 the pulley 9 is secured rigidly to pulleys 47 and 45 which are here shown as integral, and these three pulleys are revolu- 15 bly mounted upon the end of shaft 7. Adjacent the pulley 9 and revolvably mounted upon a tubular projection 53 of said pulley is a pulley 51; and between the pulleys 9 and 51 an anti-friction washer 55 is inter- 20 posed. When the cutting and grinding mechanisms are at rest this pulley 51 carries a power belt 57 (shown in Fig. 1), which may be shifted to pulley 9 when desired in order to actuate said cutting and grinding 25 mechanisms. Any suitable means for connecting these pulleys to the shaft 7 may be employed, and in the present case a friction clutch is shown, said clutch comprising a plate 59 rigidly secured to the shaft 7 by a 30 taper pin 61 and a correspondingly shaped face 63 on the interior of the pulley 45, suitable frictional material 65 being carried by said plate. This plate 59 is provided with a 35 cylindrical projection 67 which extends into a recess formed centrally in the pulley 45, a spring 69 being inserted between the end 40 of said recess and the extension or hub for normally separating the pulley 45 from the friction material. The result of this con- 45 struction and arrangement is that the belt may be shifted from pulley 51 to pulley 9 and the knife 37 thereby actuated without causing the shaft 7 to rotate. In order that the shaft 7 may be caused to rotate it is 50 necessary that the spring 69 be compressed; and the means by which the shifting of the belt and the compression of the spring are effected in the order named will now be described.

55 The pulleys 51, 9, 47 and 45 are moved to compress the spring 69 and thereby throw into operation the friction clutch by means of a slide block 71 carrying an abutment 73 which may be adjusted by means of a screw 60 74 to compensate for wear and may be held in adjusted position by means of a nut 75. This abutment contacts with a wooden block 77 set rigidly in the end of pulley 51 and is provided with a pin 79 which extends into 65 a cam slot 81 in a plate 83, said plate being

slidably mounted in a housing 85 and being held normally in its upper and inoperative position by means of a spring 87 which is supported on a projection 89 of the housing. In Fig. 3 the plate is shown in its lower or operative position and the spring consequently as compressed. The plate 83 is moved downwardly by means of a link 91 and a treadle (not shown) or any usual or desired actuating means; and said treadle may be provided if desired with a spring which may coöperate with the spring 87 or take the place of it. For shifting the belt 57 and thereby actuating the knife the plate 83 is provided with a second cam slot 93 which coöperates with a pin 95 fixed in a second slide block 97 which carries near one end a pair of fingers 99, said fingers embracing the belt and acting to shift it when the slide block 97 is actuated.

In order to take up the thrust of the clutch a ball bearing 103 is provided between the bearing 5 and the plate 59; and in order to provide a reservoir for lubricant the end of shaft 7 upon which the pulleys are mounted is made hollow.

In operation the operator moves the link 91 downwardly against the tension of the spring 87 to start the machine. This moves slide plate 83 downwardly and through the medium of cam slot 93 acting upon pin 95 first moves the belt shifter 97 to shift the power belt from loose pulley 51 to fast pulley 9 and starts the knife which is at once driven at full speed. It will be noted that slot 93 has two parts, a lower inclined part which moves the belt shifter horizontally and an upper vertical part which does not affect the position of the belt shifter at all. With this construction, assuming that the plate 83 is moved down to its lowest position, the first part of such movement will suffice to shift the belt and the latter part of the movement will be without effect. Turning now to the slot 81, said slot is seen to have its parts reversely arranged, viz.,—the lower portion is vertical and the upper portion inclined. When, therefore, plate 83 is moved downwardly the first part of its movement has no effect on the slide block 71 and hence no effect on the feeding agencies. As soon, however, as the plate reaches that point in its downward path at which the pin 79 begins to enter the inclined portion of the slot 81 the abutment 73 begins to contact with the wooden block 77 and thereby to compress the spring 69 and gradually force the acting face 63 of the pulley 45 against the friction material 65 carried by the plate 59. Since the clutch which connects the shaft 7 with the pulley 45 is a frictional one the completeness with which the speed of the pulley is imparted to the shaft depends upon the closeness of contact of the members of said clutch; and by the means 130

herein shown the closeness of this contact may be controlled at will to vary the speed at which the shaft 7, and hence the feeding instrumentalities, are driven, it being obvious that a continued downward movement of plate 83 after pin 79 has passed into the inclined part of cam slot 81 serves to move slide block 71, and hence pulley 45, into closer and closer contact with the plate 59 on shaft 7.

In actual use the operator in starting the machine depresses plate 83 by the means described until pin 95 has moved into the vertical part of slot 93. By this time the knife is being driven at full speed and the feeding instrumentalities are just being started. Thereafter the knife is constantly driven at full speed until the operator releases the treadle, while the rate at which the feeding instrumentalities act is regulated by moving the plate 83 up or down to vary the position of pin 79 in cam slot 81 and consequently the closeness of contact of the parts of the friction clutch which connects pulley 45 with shaft 7.

A third cam slot 101 similar to cam slot 93 may be formed in the lower part of plate 83 for use in case it should be desired to mount the belt shifter 97 below pulleys 51 and 9.

The invention having thus been described what is claimed and desired to be secured by Letters Patent is:—

1. The combination with a plurality of instrumentalities for acting upon stock of a belt for actuating one of said instrumentalities and a clutch for actuating the other, of a single manually controlled means for shifting said belt and one member of said clutch successively and for accomplishing the reverse movement of these elements in the reverse order.

2. The combination with a plurality of instrumentalities for acting upon stock, a shaft for driving one of said instrumentalities, and a pulley for driving another of said instrumentalities, of a single means for applying power to said pulley and shaft and for varying the speed of rotation of said shaft.

3. A skiving machine having in combination a knife, feeding mechanism and a single means for applying power successively to said knife and feeding mechanism and for varying at will the amount of power applied to said feeding mechanism.

4. A skiving machine having in combination a feed roll acting to feed stock, a knife acting to skive stock so fed and a single means for applying power to the knife and roll successively.

5. A skiving machine having in combination a feed roll acting to feed stock, a knife

acting to skive stock so fed, and a single means for applying power to the knife, for applying power to the roll, and for varying the rate at which the roll feeds the stock.

6. A skiving machine having in combination a knife, a feed roll, and a single manually operated means for applying power first to the knife and then to the roll and for withdrawing power from said knife and roll in the reverse order.

7. A machine of the class described having a cutter, feed mechanism and a source of power, in combination with an actuating member movable in a given path and provided with means arranged to act in sequence for applying power to the cutter and for progressively applying power to the feed mechanism.

8. A machine of the class described having a cutter, feed mechanism and a source of power, in combination with an actuating member manually movable in a given path and provided with means arranged to act in sequence for applying power to the cutter and for progressively applying power to the feed mechanism.

9. A machine of the class described having a cutter, feed mechanism and a source of power in combination with an actuating member manually movable in a given path and provided with cams having reversely arranged operating faces to adapt them to act successively, and means for connecting said cams respectively with said cutter and with said feed mechanism.

10. A machine of the class described having a cutting instrumentality, a feeding instrumentality and a source of power in combination with a shaft for driving one of said instrumentalities and a pulley for driving the other, said pulley and shaft being provided with clutch faces and a single means for successively applying power to one of said members and for moving the clutch faces into engagement.

11. A machine of the class described having a knife, a feed roll and a source of power in combination with a shaft for driving said roll, a pulley slidably mounted thereon for driving said knife, said pulley and shaft being provided with interengaging clutch faces, and a single means for successively applying power to said pulley and for moving said pulley along said shaft.

In testimony whereof I have signed my name to this specification in the presence of two subscribing witnesses.

EUGENE F. DAVENPORT.
